UNITED STATES PATENT OFFICE.

DICKRAN M. SARKISIAN, OF FOREST HILLS, NEW YORK.

CURTAIN TAPESTRY HOLDBACK.

Application filed March 3, 1923. Serial No. 622,486.

To all whom it may concern:

Be it known that I, DICKRAN M. SARKISIAN, a citizen of the United States, and residing at Forest Hills, county of Queens, 5 State of New York, have invented certain new and useful Improvements in Curtain Tapestry Holdbacks, of which the following is a specification.

This invention relates broadly to curtain 10 fixtures and particularly to that class of article known as hold backs.

An important object of the invention is to provide a device of the character mentioned which is inexpensive to manufacture 15 and so constructed as to be readily adapted to various styles of supports such as, for example, window casings without necessitating any change or alteration in either the device itself or the support to which the 20 device is attached.

A further object of the invention is to provide in a device of the character mentioned a simple and reliable means for locking the normally retracted or depending curtain supporting or retaining member in an 25 extended or curtain retaining position.

Other objects and certain advantages of the invention will become apparent from the 30 following description when taken in connection with the accompanying drawings in which—

Figure 1 is a fragmental perspective view of a window frame showing the device embodying my invention attached thereto.

Figure 2 is a plan view of the device showing the same applied to one particular type of frame or supporting structure.

Figure 3 is a similar view to that of Figure 2 showing the device embodying my invention applied to a somewhat modified form of frame or supporting structure.

Figure 4 is a somewhat enlarged fragmental view showing certain details of construction in elevation.

Figure 5 is a sectional view taken on line 5—5 of Figure 4.

Figure 6 is a view similar to that of Figure 4, the curtain retaining member being shown in a retracted or depending position.

In the drawings wherein for the purpose of illustration is shown what I at present consider the preferred form of my invention the numeral 5 indicates a window frame having associated therewith a curtain rod 6 upon which is supported a curtain 7 adapted

to be retained in a retracted or drawn back position, as shown, by the device embodying my invention, which comprises a bracket 8 provided with flanges 9 having ears 10 within which are formed screw holes or openings 11. The bracket 8 adjacent the flanges 9 is cut away or relieved as shown at 12 and the adjacent ends of the flanges 9 are bent at right angles as shown in Figure 6 to provide keepers or locking elements 13. These keepers or locking elements are adapted to cooperate with an elongated curtain retaining element 14, which at one end is curved to provide a hook 15. The opposite end of the curtain retaining element 14 is provided with an elongated slot or opening 16 adapted to receive a rivet or other pivot element 17 having a relatively large head 18. This pivot element functions as a means for supporting the retaining element 14 in its retracted or depending position shown in Figure 6 and functions also cooperatively with the keepers or locking elements 13 to retain the retaining element 14 in its extended or curtain retaining position shown in Figures 1 and 4. Since the flanges 9 are provided with openings 11, the device as a unit may be readily attached, as by means of screws or bolts 19, to the outer face of a suitable support such as the window frame shown in Figures 1 and 3, but if the support to which the device is to be attached is so constructed, as shown in Figure 2, that it is impracticable to readily attach the device, the openings 20 formed in the bracket may be utilized to receive the screws 21 thus making possible its practical attachment to the plain surface of the support. It will be readily appreciated therefore that the construction of the bracket 8 constituting a part of my invention is such that the device will readily accommodate itself to various types of supports without necessitating a change in either the device itself or the support to which it is desired to attach the same.

When it is desired to lock the curtain retaining element in an extended or curtain retaining position, the same may be lifted from its depending position shown in Figure 6 to its horizontal position shown in Figures 1 and 4 and thereafter so moved laterally as to urge the end of the same into the space afforded between the locking elements 13. This lateral movement, which is necessary to the locking of the curtain retaining ele-

ment 14 in its extended position, is made possible by reason of the fact that the opening 16 is sufficiently elongated to permit the pivot end of the element 14, after being 5 swung from its depending position to a horizontal position to be urged into the space afforded between the locking elements 13.

Having thus described my invention I claim:

- 10 1. A device of the character described comprising a bracket having a pair of flanges, a curtain retaining element pivotally and slidably connected to said bracket, the pivotal end of said curtain retaining element 15 being adapted to be swung about its pivotal connection with said bracket and thereafter moved transversely to the axis of its pivotal connection with said bracket into the space afforded between said flanges whereby the 20 curtain retaining element is locked in curtain-retaining position.
2. A device of the character described comprising a bracket having a pair of flanges, the ends of said flanges being bent 25 at right angles to provide a pair of locking elements spaced from each other, a curtain retaining element pivotally and slidably connected to said bracket, the pivotal end of said curtain retaining element being adapted 30 to assume a position intermediate said locking element whereby the curtain retaining

element is locked in curtain retaining position.

3. A device of the character described comprising a bracket having a pair of spaced locking elements associated therewith, a curtain retaining element having a slot formed thereon, a pivoted element passing through said slot for pivotally and slidably connecting said retaining element to said bracket, the pivotal end of said retaining element being adapted to be swung about said pivoted element and thereafter slid upon the same into position intermediate said locking elements. 45

4. A device of the character described comprising a bracket having a flange carried thereby, said flange being struck up to provide a pair of spaced locking elements, a curtain retaining element having a slot formed thereon, a pivot element passing through said slot for pivotally and slidably connecting said retaining element to said bracket, the pivotal end of said retaining element being adapted to be swung about said pivotal element and thereafter slid about the same 50 into position intermediate said locking elements. 55

In testimony whereof, I have affixed my signature to this specification.

DICKRAN M. SARKISIAN.
